KNOB FOR DOORS, DRAWERS AND THE LIKE

Alfred H. Bottom, Canton, Ohio, assignor to American Home Products Corporation, New York, N.Y., a corporation of Delaware

Filed Jan. 20, 1966, Ser. No. 694

Term of patent 14 years

(Cl. D10—8)

Fig. 3

FIG. 1 is a front elevational view of a knob for doors, drawers and the like embodying my new design.

FIG. 2 is a side elevation.

FIG. 3 is a sectional view taken along line 3—3 of FIG. 1 as viewed in the direction of the arrows.

I claim:

The ornamental design for a knob for doors, drawers and the like, as shown.
